UNITED STATES PATENT OFFICE.

DAVID A. SHORT, OF CINCINNATI, OHIO, ASSIGNOR OF ONE-THIRD TO EUGENE F. SPENCER, OF DAYTON, KENTUCKY, AND ONE-THIRD TO ALEXANDER REID, OF COLLEGE HILL, OHIO.

PROCESS OF MAKING GAS.

No. 868,710.

Specification of Letters Patent.

Patented Oct. 22, 1907.

Application filed May 2, 1907. Serial No. 371,371.

To all whom it may concern:

Be it known that I, DAVID A. SHORT, a citizen of the United States, residing at Cincinnati, in the county of Hamilton and State of Ohio, have invented certain new and useful Improvements in Processes of Making Gas, of which the following is a specification.

My invention relates to a process of making gas and utilizing the heat products thereof, the object of this invention being to utilize the heat of the gases produced by a producer gas apparatus to distil coal in retorts to make ordinary distilled gas and to then utilize the coke from said retorts in the producer gas apparatus.

A further object of the invention is the process of means for utilizing the heat products from the producer gas apparatus to generate steam.

A further object of the invention is the production of a fixed gas consisting of a mixture of producer gas and distilled gas and the utilization of all the heat producing powers of the fuel from which said gas is obtained.

20 Further objects and advantages of the invention will be set forth in the detailed description which now follows.

In the accompanying drawing: Figure 1 is a side elevation of a gas producing apparatus constructed in accordance with the invention, and, Fig. 2 is a vertical section therethrough.

It is to be understood that the apparatus herein shown and described, forms no part of the present invention, except in so far as it illustrates means for carrying out 30 the process which I have invented.

Numerous other mechanical devices might be substituted for those herein shown and described, the invention residing in the novel process hereinafter set forth.

In the drawing, the numeral 5 designates a gas producer of any desired type. The gas generated by this producer passes through an opening 6 to the interior of the casing 7, this casing being formed partially of metal and partially of fire brick. Retorts 8 are arranged within this casing, preferably at an angle of about forty-five 40 degrees, though this angle may be varied at will, or the retorts may be horizontal or vertical. The lower ends of these retorts are closed by doors 9 of any suitable material.

A steam generator 10 is located beneath the retorts 45 and a mixer 11 is also located beneath said retorts and preferably above the generator.

Hoppers 12 communicate through spouts 13 with spiral conveyers 14, said conveyers being adapted to convey fuel to either of the oppositely inclined retorts 50 through the tubes 15.

Pipes 16 extend through the casing 7 and communicate through branch pipes 17 with the retorts, these pipes serving to convey the distilled gas from the retorts to the mixer 11, it being understood that this mixer

11 may be of any desired type. A tee 18 leads from the 55 end of the casing 7 and a pipe 19 leads from said tee. Another pipe 20 leading from the opposite side of said tee, extends to the steam generator 10. A pipe 21 which extends from the opposite end of the generator establishes communication between said generator and 60 the mixer 11, this mixer being illustrated in dotted lines in Fig. 1. A branch pipe 22 communicates with the pipe 16 and is adapted to convey the distilled gas from the retorts to any desired point. Pipes 23 extend along the casing 7 at the lower ends of the retorts and 65 are adapted to receive the tar from said retorts and to convey said tar to the producer gas apparatus through a branch pipe 24.

The operation of the device is as follows: The very hot producer gas passes through the casing 7 and around 70 the retorts 8 distilling the coal contained in said retorts and producing distilled gas from said retorts. This distilled gas passes through the pipes 16 to the mixer, or if it be desired to use this distilled gas, it may be taken off through the branch pipe 22. After the producer gas 75 has passed through the casing 7, it passes through the pipe 20 and through the generator 10 where its heat is there utilized to generate steam in the usual and well known manner. After passing the steam generator, the producer gas goes through the pipe 21 to the mixer 11. 80 Ordinarily the distilled gas from the retorts, will be taken through the pipes 16 to the mixer 11, the distilled gas and the producer gas being here mixed to make a fixed gas of the whole.

If it be desired to utilize the producer gas without 85 mixing it with the distilled gas, this producer gas may be taken off through the branch pipe 19. After the coal in the retorts has been distilled to produce the distilled gas, the remaining coke is removed from the retorts through the doors 9 and conveyed in any desired manner to the producer gas generator 5, where every particle of gas is extracted from it and where the heat from said coke is still further utilized in distilling more coal in the retorts. The tar conveyed to the producer gas apparatus, is also utilized in the production of producer 90 gas. It will therefore be seen that every particle of heat producing power contained within the fuel delivered to this apparatus, is utilized. Ordinarily, producer gas is passed through a cooling device before being delivered to the mixer. The heat units lost in cooling this gas, represent a direct waste and by virtue of the process herein set forth, these heat units may be 95 saved.

What I claim, is:

1. A process of making gas which consists in making 105 producer gas conducting said producer gas to retorts containing coal and distilling said coal by the heat of said producer gas and then passing said producer gas through

- a steam generator and then mixing said producer gas with the distilled gas to form a fixed gas of the whole.
2. A process of making gas which consists in making producer gas passing said gas about retorts containing coal and distilling said coal by the heat of said producer gas, then passing said producer gas through the flues of a steam generator without igniting said gas and then mixing said producer gas with the distilled gas to form a fixed gas of the whole, and then utilizing the coke from said retorts in the producer gas generator. 15
5. A process of making gas which consists in making producer gas passing said gas about retorts containing coal and distilling said coal by the heat of said producer
10. A process of making gas which consists in making producer gas passing said gas about retorts containing coal and distilling said coal by the heat of said producer

gas, then passing said producer gas through the flues of a steam generator without igniting said gas, then mixing said producer gas with the distilled gas to form a fixed gas of the whole, and then utilizing the coke from said retorts in the producer gas generator.

In testimony whereof I affix my signature in presence of two witnesses.

DAVID A. SHORT.
